UNITED STATES PATENT OFFICE.

WILLIAM H. WILDER, OF GARDNER, MASSACHUSETTS.

OIL-STOVE.

SPECIFICATION forming part of Letters Patent No. 645,154, dated March 13, 1900.

Application filed March 14, 1899. Serial No. 709,052. (No model.)

To all whom it may concern:

Be it known that I, WILLIAM H. WILDER, a citizen of the United States, residing at Gardner, State of Massachusetts, have invented 5 certain new and useful Improvements in Oil-Stoves, of which the following is a specification.

My invention relates to oil-stoves of the class heretofore invented by me, in which a 10 reservoir is used having a maintained oil-level, and there is a relative movement either of the burner or reservoir, so as to raise or lower the level of the oil in the burner. In Patent No. 595,231, dated December 7, 1897, 15 I have shown a stationary burner and a movable reservoir. In Letters Patent No. 618,020, dated January 17, 1899, I have shown a form of stove having the reservoir stationary and the burner movable. In the present invention 20 the same object is sought—namely, to raise or lower the oil in the burner; but instead of having one part movable and the other part stationary I may make both parts movable, and thus secure the same action as 25 in the patents referred to, but the vertical movement of the parts is reduced one-half for the reason that the arrangement is such that as the burner lowers the oil-chamber rises, and vice versa, and consequently much less 30 movement is required than where one of the said parts alone moves. The present invention also includes parallel bars for connecting and giving the necessary movement to the parts, whether both are movable or only one, 35 and a duct connecting the burner and oil-chamber having a swiveled connection, so as to allow of the movement of one or both parts.

In the accompanying drawings I have shown a conventional form of the invention 40 in side elevation in Figure 1, while Fig. 2 is a plan view of Fig. 1. Fig. 3 shows the oil-chamber stationary and the burner movable. Fig. 4 is a plan view of Fig. 3.

In the figures, A may represent any suitable standard, and swinging thereon are parallel bars $e e'$, pivoted at one end to the burner B and at the opposite end to the oil-chamber C. A handle D is secured to the upper bar e, projecting outwardly therefrom, having an 45 angular extension, so as to give a proper leverage to work the bar e to move the oil-holder and oil-chamber connected therewith.

The oil-holder of the burner B is preferably of the construction shown in my prior patents, but may be of any form suitable for the 55 purpose. The oil-chamber C is adapted to contain a reservoir similar to that shown in my former patents and furnishes a maintained oil-level, as has been fully described heretofore in the patents referred to. The oil is fed 60 from the chamber C to the burner through a duct or passage E, offset, as shown, and having a swivel connection at each end to allow of the movement of the parts. The bar e' supports the pipe b, extending from the oil-chamber 65 C and the pipe a of the burner, and with these pipes the swivel connection is made with the offset E. In order that the burners may be well drained, I arrange the pipe F, connecting the sides of the burner, on a slight 70 incline from the point a'.

A modification of the parallel bars may be utilized as a convenient means of raising and lowering one of the parts in relation to the other, as shown in Figs. 3 and 4. In these 75 figures the oil-chamber is stationary and the burner is movable, being connected to the oil-chamber C directly by the bar e^2 without the interposition of a central post or standard, as in Figs. 1 and 2, and the duct itself serves 80 as the second bar, as shown at E'. This connection gives a positive movement and always maintains the movable part, whether it be the burner or oil-chamber, in a level or horizontal position. In Figs. 3 and 4 the handle 85 is shown at D'.

Having thus described my invention, what I claim is—

1. In an oil-stove, an oil-chamber having a maintained oil-level, a burner and means for 90 moving both of said parts in unison but in reverse direction, substantially as described.

2. In an oil-stove, an oil-chamber having a maintained oil-level, a burner, means for moving said parts in unison but in opposite directions and a swiveled pipe connection between the parts, substantially as described. 95

3. In an oil-stove, an oil-chamber having a maintained oil-level and a burner, one of said parts being vertically movable, an oil-supply 100 pipe connected with said burner at two points, said pipe being inclined from one side to the other so as to perfectly drain the burner and a suitable pipe connection between the end of

- the pipe and the oil-chamber, substantially as described.
4. In an oil-stove, an oil-chamber, a burner, said parts being movable and parallel bars 5 pivotally connected to said parts, the oil-chamber being in communication with the burner, substantially as described.
5. In an oil-stove, an oil-chamber, a burner, said parts being movable, parallel bars pivotally connected to said parts and an offset oil-duct having swiveling connections with the oil-chamber and burner, substantially as described.
6. In an oil-stove, an oil-chamber, a burner, 15 said parts being movable and in communication with each other, parallel bars connecting the parts and a supporting-standard for the parallel bars, substantially as described.
7. In an oil-stove, an oil-chamber having a maintained oil-level, a burner, and an offset oil-duct having swiveled connections therewith, substantially as described. 20
8. In an oil-stove, an oil-chamber having a maintained oil-level, a burner, and an oil-duct between, having swiveled connection therewith, substantially as described. 25
9. In an oil-stove, an oil-chamber, a burner, and a connection between the parts comprising a straight bar and an oil-duct, substantially as described. 30

In testimony whereof I affix my signature in presence of two witnesses.

WILLIAM H. WILDER.
